ORTHOPEDIC SHOE HEEL

Joseph Pietzuch, St. Louis, Mo.

Application May 14, 1934, Serial No. 725,532

6 Claims. (Cl. 36—35)

5 My invention relates to an orthopedic shoe and heel construction, and particularly to a unique design of heel for shoes which will cause the wearer of the shoe incorporating my invention to automatically assume a correct foot position when standing or walking, and which will by reason of a correct distribution of the weight on the feet relieve undue strains on the inner, outer, and transverse arches of the feet, thus 10 producing ease and comfort of the feet in standing or walking.

15 It is a well known fact that a person throws more or less weight or strain to the inside or outside arches of the feet when walking or standing, as illustrated by the crooked and uneven wearing of the heels and also the soles of the shoes. This indicates that an increased strain is thrown upon either the inner or outer longitudinal arches or the transverse arch, and this 20 condition ultimately breaks down the main supporting foot arches and results in the painful condition usually known as "flat foot", which in addition destroys correct body poise, springiness of step, and general walking efficiency, as well as 25 causing serious personal inconvenience and distress.

30 Human feet may be divided into three classes: the first class is the rigid foot, the second class the flexible foot, and the third class the flat foot. The rigid foot is of very firm and strong nature and correctly supports the weight of the body, the bones of the foot lying in a natural arched position so that the weight is supported at the heel and toe regions of the foot. This is 35 the most perfect type of foot and is usually found in persons who are physically strong and whose feet are disposed in a proper or correct position when standing or walking. The flexible type of foot is one which has some flexibility and in 40 which the muscles and arches of the foot have been somewhat strained so that the desired rigidity is not present. The third class of foot, or flat foot, is one in which the arches are completely broken and there is neither rigidity nor flexibility.

45 Approximately 10% of the feet are of the rigid type, 25% are of the flat foot type, and the remaining 65% are of the flexible type. If persons having feet of the flexible type continue to walk 50 or stand with the feet in improper positions to take the weight of the body, a flat foot will develop. If a person having flat feet will place or be caused to place his feet in such positions as to relieve excessive strains on any of the arches, the flat foot condition cannot be corrected but

5 painful and distressing conditions may be relieved.

In my prior patent entitled Shoe-heel cushion, No. 1,264,127, patented April 23, 1918, is disclosed a heel which is particularly adapted to be worn by persons having flat feet. This type of heel will distribute the weight on the feet in such a manner as to relieve pain and distress. Such heel, however, is not adapted for use on the flexible or rigid type of foot, since by reason of its 10 design the weight will be thrown onto the outer arch of the foot, with the result that it will be unduly strained.

15 After considerable investigation and experimenting in an effort to invent a heel construction adapted for use by persons having the rigid type or the flexible type of foot, I have discovered certain principles which I have put into use in the present invention and have thus produced a heel construction which is peculiarly 20 adapted for use by persons having rigid or flexible feet.

25 In the first place, I have determined that it is necessary to properly distribute the weight on the inner, outer, and transverse arches of the feet. This may be accomplished by placing the foot on a desired vertical or upright axis. I use the term "vertical axis" arbitrarily and by it I mean an axis which extends in a plane substantially, but not necessarily accurately, perpendicular to 30 the surface on which the foot is placed. By tilting the foot either inward or outward; that is, to throw the weight on the outer arch or the inner arch, I am able to distribute the weight on the arches of the feet in desired proportions 35 so that one arch does not receive any more load than it is intended to carry or due to its physical condition is able to carry. This tilting of the foot I refer to as adjusting the position of the foot on a vertical axis. I have further determined that by causing a person to place his foot 40 in a proper standing or walking position, the foot structure is much more able to take the load on the foot than when the foot is in an improper position. This is readily appreciable due to the 45 fact that usually foot pains or breaking down of the arches or straining of the arches results originally from improper foot position. I therefore have determined that in addition to the adjustment of the position of the foot on the vertical axis, it is necessary to adjust the foot on a horizontal axis. I use the term "horizontal axis" 50 arbitrarily to mean the axis which extends from the heel to the toe of the foot. In other words, I refer to the moving of the foot to cause the 55

5 toe to point either forward or inward. I have determined from the experiments which I have made that by properly adjusting the foot both as to its vertical axis and as to its horizontal axis, a proper walking position will be assumed and that the weight will be evenly distributed over the various parts of the foot which are intended to take the weight.

10 It is an object of my present invention to provide an orthopedic shoe and a heel construction in which the foot will be properly adjusted both on its vertical axis and its horizontal axis, as pointed out heretofore, in order that proper walking position and proper weight distribution will be obtained. When a shoe including my invention is worn by a person having a rigid type of foot, the foot will be supported in a proper walking position and there will be no tendency for the arches to be either strained or broken. When the shoe 15 incorporating the features of my invention is worn by a person having flexible feet, ease and pleasure in standing or walking will be produced and any defective condition will not be aggravated. By wearing a shoe of my invention 20 over a period of time the arches and muscles of the flexible type of foot will be permitted to be strengthened due to the fact that undue strains are not placed on any part of the foot.

25 One very important point which I have determined is that the foot must be brought into a correct position prior to the time that the weight is placed on the arches of the foot. During walking when a person steps out, for example, with his right foot, he first places the rear edge of the heel on the floor, then as he walks forward the toe is brought down and finally the weight is placed on the arches or on the foot as a whole. During the initial stepping position all of the 30 weight is taken by the heel and particularly is applied through the os calcis, which is the bone of the foot in the heel. I have determined that the proper time to adjust the foot on the horizontal axis is while the os calcis is taking the weight and before the weight is transferred to the 35 arches of the foot.

40 It is, in accordance with the above paragraph, an object of my invention to provide a shoe construction and a heel therefor in which the foot is adjusted on its horizontal axis prior to the time that the weight is placed on the arches of the feet.

45 In order to illustrate my invention, I will describe a particular embodiment of my invention, reference being had to the accompanying drawing.

50 Referring to the drawing:

Fig. 1 is a plan view looking downwardly as indicated by the line and arrows A—A of Fig. 5 of a heel incorporating the features of my invention adapted to be secured to a right shoe.

55 Fig. 2 is a plan view looking downwardly as indicated by the line and arrows A—A of Fig. 5 of a heel incorporating the features of my invention which is adapted to be secured to a left shoe.

60 Fig. 3 is a vertical sectional view through a shoe incorporating the features of my invention and having the heel of Fig. 1 attached thereto. Diagrammatically illustrated in this view is a foot showing the bone and arch construction.

65 Fig. 4 is a plan view of the sole and heel construction of the shoe shown in Fig. 3, the sole 70 which all of the weight is being taken by the os calcis and immediately prior to the time the weight is distributed to the arches of the foot.

75 Fig. 4 is a plan view of the sole and heel construction of the shoe shown in Fig. 3, the sole

and heel being shown in full lines in order that the invention may be clearly illustrated.

Fig. 5 is a section taken as indicated by the line 5—5 of Fig. 4.

Referring to Figs. 3 to 5 inclusive, the numeral 11 represents the shoe having an upper or top construction 12, a sole 14, and a heel 15. This heel 15 incorporates the novel features of my invention and is illustrated in Figs. 1 and 2. Fig. 1, as pointed out heretofore, is a plan view of the 10 heel employed on the right shoe, and Fig. 2 is a plan view of the heel worn on the left shoe. In describing the construction of the heel, reference will be made first to Fig. 1. The heel 15 is made of an external shape which resembles the ordinary heel construction. It has a relatively straight forward lateral face 16, side curved faces 17, and a rear curved face 18. The faces 17 and 18 are of curved shape in order to conform to the contour of the shoe to which they are secured. 15 I have found that it is very important that the face 16 be straight in order to give a slightly greater area to the forward inside corner while preserving the original appearance to the average observer and to give the desired adjustment of 20 the shoe on its vertical axis, as will be fully explained hereinafter. I have found this to be particularly true in the better made shoes in which the soles and shanks are quite flexible and, therefore, require the support offered by the 25 straight forward wall 16.

The heel of my invention is made in two parts and is of dual resiliency. In other words, one part of the heel is more resilient, elastic, or flexible, than the other part. Due to the fact that 30 rubber may be made of different resiliencies or elasticities and possesses the necessary wear-resistant qualities, I prefer to make the heel from rubber. For the purpose of distinguishing between the two sections, I use the terms "resilient" 35 and "less resilient". It should be understood, however, that these terms are only relative. I have found in actual practice that very satisfactory results are obtained where the resilient portion is substantially 75% resilient and where the less resilient portion is substantially 25% 40 resiliency. It is highly desirable that both portions of the heel have both wear and weather-resistant qualities in order that the heel will retain its shape over a long period of time and 45 will not wear nor change its shape due to weather conditions. It is particularly desirable that the more resilient portion have substantially greater wear-resistant qualities so that at the end of the life of the heel, the entire wear surface will still 50 be substantially plane.

The numeral 20 represents a resilient portion and the numeral 21 represents a less resilient portion of the heel 15 of my invention. These two portions are preferably formed integrally 60 and their line of juncture is along a diagonal line 22. The position of the line of junction 22 of the two portions 20 and 21 of the heel of my invention is very important, since it enables the accomplishment of the important and unique 65 results obtainable in the use of my invention. It will be noted that this diagonal line 22 is a transverse line extending from one side 17 to the other side 17 of the heel, with the result that there is a less resilient material on both the inner and outer sides of the shoe. Since Fig. 1 shows a heel adapted for use on a right shoe, the numeral 24 will represent the inner side and the numeral 25 will represent the outer side. From the inner side 24 to the outer side 25 the dividing 70 75 80 85 90 95 100

line 22 extends diagonally forward. It is important to the invention that the less resilient material on the inner side of the heel extend farther to the rear than on the outer side of the heel. It is, moreover, important that the less resilient material extend all the way across the heel; that is, all the way from the inner side 24 to the outer side 25. The exact angle which the dividing line 22 makes with respect to a longitudinal or transverse axis through the heel is not vital so far as a number of degrees are concerned, but it must be of such an angular position that the results of my invention, which I will point out in detail hereinafter may be accomplished; and after reading that portion of the specification the exact requirements and tolerances of the particular shape or dimensions may be understood.

In Fig. 2, which is a heel adapted to be secured to a left shoe, the construction is reversed, as is obvious from a comparison of Figs. 1 and 2, and therefore the numerals employed in Fig. 1 may be applied to the heel shown in Fig. 2.

In Figs. 3 and 5 I have shown the bones of the foot and have placed the names on them so that they may be readily recognized. Referring now particularly to Fig. 3, I will describe the manner in which the shoe incorporating the features of my invention will cause an even distribution of the weight on the various parts of the foot and a correct walking or standing position thereof.

In Fig. 3 I have shown the position of the outwardly toed right foot and shoe just at the point after the rear edge or rear portion 30 has engaged the surface 31. The weight has been applied to the rear portion of the heel at this time and due to the fact that the rear portion of the heel is the resilient portion 20, it will be compressed and deformed slightly, as illustrated in Fig. 3. It is highly important that the two portions 20 and 21 be permanently secured together and be integral in order that when the part 20 is compressed it will not be pulled away from the part 21. The lower faces which are in the same plane always meet at a common juncture point and there is no offsetting relation at the juncture point caused by a compression of the part 20. The resilient portion of the heel therefore performs the very valuable service of acting as a shock absorber in order to absorb the force of the original contact of the heel with the surface 31. The foot and shoe are shown in the position just prior to the time that any part of the less resilient portion 21 comes into contact with the surface 31.

Considering now that the foot has moved slightly from the position shown in Fig. 3 and that the rear inside corner of the less resilient portion has come into contact with the surface 31, due to the fact that the inner portion of the less resilient part of the heel extends sufficiently farther to the rear than the outer portion, the inner less resilient portion will come into contact with the surface prior to the time that the outer less resilient portion comes into contact with the surface 31. This occurs while the weight is transferred to the surface through the os calcis or through the bone in the heel. This is prior to the time that the weight is shifted to the arches or the bones constituting the arches of the foot. When the inner rear corner of the inner less resilient portion, which I will designate by the numeral 33, and which is indicated by the point or small area as shown in Fig. 4, engages the surface 31, there is a tendency for the foot

to be rotated in a counterclockwise direction, as indicated by the arrow 34 in Fig. 4. This rotating action is produced due to the fact that this inner rear corner of the less resilient portion offers greater resistance to the pressure applied in taking a step, the direction of pressure being indicated by the arrow in Fig. 3. Due to the fact that this inner rear corner of the less resilient portion is eccentric with respect to the axis C—C, as shown in Fig. 5, there will be a rotating force, 10 as indicated by the arrow 34 in Fig. 4, which tends to swing the shoe from the position indicated in full lines in Fig. 4 into such a position that the axis A—A will now occupy the position indicated by the dotted axis line B—B. The result of this rotating action is to move the shoe and foot from a position shown in full lines in Fig. 4 and disposed on an axis A—A into a position in which the foot and shoe will be disposed on an axis B—B. In other words, the toe of the 20 shoe and foot will be swung inwardly. Fig. 4 is a plan view showing the sole and heel construction of the right foot and the foregoing description applies thereto. However, it will be understood that in a shoe for the left foot the heel 25 is arranged as shown in Fig. 2 and the rotating of the shoe on a horizontal plane would be in the opposite direction. It is well known that the correct walking position of the foot is slightly pigeon-toed. This is the position in which the 30 American Indian holds his foot while walking and it is well recognized that this is the natural and correct walking position of the foot. This is the adjustment of the portion of the foot which is referred to as the adjustment on a horizontal 35 axis.

Thus far we have brought the foot into a proper walking position. It further remains, however, to position the foot so that the weight is properly distributed between the inner and outer 40 arches. As the foot reaches the position in which the weight is placed on the arches, the major portion of the heel will be brought into contact with the surface 31 and the less resilient portion 21 will engage the supporting surface 31 entirely 45 across the heel. In other words, there will be engagement from the inner side to the outer side of the heel. Due to the fact that this portion 21 is a flat less resilient portion, it will cause the shoe and foot to assume its proper vertical position, as shown in Fig. 5. It is this condition of the heel of my invention which produces an adjustment of the shoe and foot on or around the vertical axis C—C as indicated by the arrow 35. It will be seen that if in stepping 55 forward the foot is tilted either inward or outward, the less resilient portion 21 will properly tilt the shoe and foot into their proper vertical position relative to the axis C—C. When in this position the weight will be properly distributed on the arches of the foot so that no part of the foot will be subjected to undue strains.

From the foregoing it will be seen: first, that the shoe incorporating the features of my invention causes the foot to automatically assume a proper walking posture; second, that the foot is brought into its proper horizontal position prior to the time that the weight is transferred to the arches of the foot and during the time that 70 the weight is carried by the os calcis; and third, that the foot is adjusted on its vertical axis in order that the weight will be properly distributed to the inner and outer arches. A fourth result 75

and advantage of the invention is that the foot is not unduly pinched or cramped in the shoe, since it will rest in a normal central position and will not be thrown to the outer or inner walls of the shoe which would produce an uncomfortable or distressed condition.

I claim as my invention:

1. A heel construction comprising a body of rubber having front and rear portions integrally secured together along a transverse line of substantial slope, the rear portion being formed of resilient rubber and the front portion being formed of less resilient rubber only, said transverse line extending forwardly from the inner to the outer edge of said heel and the middle of said transverse line being positioned forwardly of the center of the heel to provide the inner side of said front portion with a substantially greater area than the outer side of said front portion.
2. A heel construction comprising a body of resilient material having front and rear portions which are integrally secured together, the front portion being of less resilient material than the rear portion, the area constituting the inner side of said front portion extending rearward beyond the hook of the os calcis to provide a support therefor, and the area constituting the outer side of said front portion being sufficient to provide a support for only the forward outer portion of the os calcis.
3. A heel construction comprising a body of rubber having front and rear portions integrally secured together, the front portion being of less resilient material than the rear portion, the inner side of said front portion extending rearward beyond the hook of the os calcis and the outer side of the hook portion extending rearward a sufficient distance to provide a support for only the forward outer portion of the os calcis.
4. A heel construction comprising a body of resilient material having front and rear portions integrally secured together along a transverse diagonal line, the front portion being of less resilient material than the rear portion, the inner side of said front portion extending rearward beyond the hook of the os calcis and the outer side of said front portion extending rearward beyond only the forward outer portion of the os calcis.
5. In an orthopedic shoe construction of the class described having a sole and upper construction, the combination with a heel secured to the heel portion comprising a body of rubber having front and rear portions integrally secured together along a transverse line of substantial slope, the rear portion being formed of resilient rubber and the front portion being formed of less resilient rubber only, said transverse line extending forwardly from the inner to the outer edge of said heel and the middle of said transverse line being positioned forwardly of the center of the heel to provide the inner side of said front portion with a substantially greater area than the outer side of said front portion.
6. In an orthopedic shoe construction of the class described having a sole and upper construction, the combination with a heel secured to the heel portion, comprising a body of resilient material having front and rear portions which are integrally secured together, the front portion being of less resilient material than the rear portion, the area constituting the inner side of said front portion extending rearward beyond the hook of the os calcis to provide a support therefor and the area constituting the outer side of said front portion being sufficient to provide a support for only the forward outer portion of the os calcis.

JOSEPH PIETZUCH. 40
